CLAIM

The ornamental design for cell therapy manufacturing cabinet as shown and described.

DESCRIPTION

FIG. 1 is an isometric view of a cell therapy manufacturing cabinet according to an embodiment of the present invention;

FIG. 2 is an end view thereof;

FIG. 3 is an opposite end view thereof;

FIG. 4 is a side view thereof;

FIG. 5 is a top view thereof; and,

FIG. 6 is a bottom view thereof.

The broken lines illustrate portions of the cell therapy manufacturing cabinet that form no part of the claimed design.

1 Claim, 6 Drawing Sheets
